(57) CLAIM

I claim the ornamental design for a hanging bust carrier, as shown and described.

DESCRIPTION

FIG. 1 illustrates a perspective view of a hanging bust carrier of the present invention;

FIG. 2 illustrates a front view of the hanging bust carrier of the present invention;

FIG. 3 illustrates a right side view of the hanging bust carrier of the present invention, the left side view of the hanging bust carrier being a mirror image;

FIG. 4 illustrates a rear view of the hanging bust carrier of the present invention;

FIG. 5 illustrates a top plan view of the hanging bust carrier of the present invention; and,

FIG. 6 illustrates a bottom view of the hanging bust carrier of the present invention.

The broken lines of FIGS. 1–6 are for illustrative purposes only and form no part of the claimed design.
